UNITED STATES PATENT OFFICE.

ROBERT E. LEE FREESE, OF FAYETTE, MISSOURI.

FENCE-WIRE STRETCHER.

1,275,896.

Specification of Letters Patent. Patented Aug. 13, 1918.

Application filed October 19, 1916. Serial No. 127,132.

To all whom it may concern:

Be it known that I, ROBERT E. L. FREESE, a citizen of the United States, and a resident of Fayette, in the county of Howard and State of Missouri, have made an Improvement in Fence-Wire Stretchers, of which the following is a specification.

My invention is an improvement in the class of wire stretchers in which a winding 10 drum or windlass and wire rope are employed in connection with means for attachment of the apparatus to a post or tree-trunk.

The details of construction, arrangement 15 and operation of the parts composing the invention are as hereinafter described and illustrated in the accompanying drawing, in which:—

Figure 1 is a plan view, and,

Fig. 2 is a side view of my improved structure.

Fig. 3 is a side view of the pivot end of the lever 8.

The frame of the apparatus comprises a 25 tubular body 13 having angular lateral extension 14. A rectangular bar 3 is adapted to slide freely in such body 13, and is of greater length so that it projects at each end thereof.

One end of said bar has a rigid alined 30 strap extension 5, to whose outer extremity an eye 38 is attached to provide for detachable connection of block and tackle. The opposite end 6 of the slide bar 3 is forked 35 to form a jaw adapted to engage a fence-post (not shown).

Another jaw 47 having a curved shank 10 is pivoted between parallel ears or lugs 18, which form a rigid and permanent attachment 40 of one end of the angular frame extension 14. Both jaws 6 and 47 are roughened or toothed to enable them to take a firm grip of a fence-post. Holes 20 are provided in the ears 18 and the hole 46 in the jaw shank 45 10 for insertion of a stop-pin (not shown).

The slideable bar has a shallow lengthwise groove 7, whose bottom is provided with ratchet teeth. A lever 8 is pivoted on the side of the hollow body 13 between the parallel ears 22, and its pivot end 39 is constructed with a prong or dog 8^a adapted to engage the ratchet teeth for a purpose hereinafter stated. A loop 23 is hinged to the body 13 and is adapted to swing over the nose of

lever 8. Its function is to hold the lever 55 in place against the body 13, when the apparatus is not in use. A small chain 25^a is provided for engagement with a prong 25 on the free end of the lever 8, to hold the latter locked in position when engaged with the 60 ratchet bar 3. When not in use, the chain 25^a may be wrapped around the loop 24.

The function of the lever 8 and its dog which engages the ratchet of the slideable bar 23, is to force the jaw 6 into firm engagement with the post, or in other words to cause the two jaws to take and hold a firm grip on the post, and when this has been effected, the chain 25^a is wrapped around the loop 24 to keep the lever duly locked 70 with the ratchet.

In the frame of the apparatus, there is journaled a windlass 28 on whose outer end are mounted a cog gear 31 and ratchet wheel 33 with which a pivoted pawl 34 engages. 75 The said gear meshes with a pinion 29, mounted on a shaft 30 and having a hand crank on its outer end, as shown.

Block and tackle are provided as shown, one block being attached to the eye 38 at the 80 extremity of the ratchet bar attachment 5, and the other block has a wire gripper 11. A wire rope is rove through the two blocks and its respective ends are attached to the windlass and one of the blocks, as shown. 85

It is apparent that the jaws 6 and 47 having been applied to a post, and the lever 8 duly manipulated to cause them to grip the latter firmly, and the block and tackle having been duly engaged with the frame and 90 the wire to be stretched, the crank is rotated, whereby the rope is wound on the windlass, thereby drawing the wire past the post and stretching it to the desired tension. I thus provide a wire fence-stretcher of simple and 95 inexpensive construction, and which may be efficiently operated for its purpose.

I claim:—

In a fence wire-stretcher of the type described the combination with a tubular body, 100 and a ratchet bar adapted to slide therein, of a lever pivoted to said body and having a pivoted feed and locking dog engaging the ratchet proper, and means attached to the body and adapted for engaging the free end 105 of the lever, as and for the purpose specified.

ROBERT E. LEE FREESE.
